UNITED STATES PATENT OFFICE.

JAMES D. MORRISON, OF REINBECK, IOWA, ASSIGNOR TO THE MORRISON
CONVERTIBLE CAR SEAT COMPANY, OF CHICAGO, ILLINOIS.

RAILWAY-CAR.

SPECIFICATION forming part of Letters Patent No. 497,677, dated May 16, 1893.

Application filed October 1, 1892. Serial No. 447,470. (No model.)

To all whom it may concern:

Be it known that I, JAMES D. MORRISON, a citizen of the United States, residing at Reinbeck, in the county of Grundy and State of Iowa, have invented a new and useful Improvement in Railway-Cars, of which the following is a specification.

My invention relates to an improvement in the class of convertible day-coaches, the seats 10 of which are adapted to be converted into sleeping-berths; and it relates particularly to an improvement in the construction of the convertible seat forming the nucleus of the invention in railway-cars for which Letters 15 Patent of the United States No. 475,791 were granted to me on the 31st day of May, 1892.

Generally stated, my aforesaid patented invention involves the seats of a passenger day-coach rendered convertible into sleeping-20 berths by providing alternate seats with separable seat-portions connected with the seat-bases by means of folding sections extensible upward to elevate the seat-portions into and support them in position for upper sleeping-25 berths; the backs of the seats are adjustable in the direction of alignment with the seat-portions to extend the couch at either side thereof, separable and adjustable means being provided for extending the couch at the 30 opposite side, and means are also provided for supporting the raised seat-portions at their inner or wall-ends and for supporting the seat-extensions for the couch. Thus the upper berths are formed with alternate seats 35 in the car, the intermediate ones not requiring that their seat-portions be separable and adapted to be raised, but having their backs adjustable to form extensions in either direction of the couch-portions for lower berths 40 and being provided with separable means adjustable for extending the couch-portions in the opposite direction.

The primary object of my present improvement, while retaining the broad principle contained in my aforesaid patented invention of the separable seat-portions of the seats connected with the seat-bases by means of folding upward extensible connections for use in supporting the seat-portions in position for 45 upper sleeping-berths, is to simplify and better the construction by dispensing with any

details requiring separation from the seat-structure to adjust it into its seat-form and re-adjust it into place to form the berth.

A further object is to render self-supporting 55 the extensions of the seat-portion when adjusted to form a couch; and a still further object is to provide sectional means for connecting the separable seat-portions with their bases and which are extensible upward to 60 elevate and support the seat-portions in position for upper berths, the construction of which connecting-means shall adapt them to fold against the seat-bases in the direction transversely thereof. 65

To accomplish my first-named object, I provide a seat, or each seat to be converted, whether into an upper or a lower berth, with two swinging backs, hinged or pivoted for opposite sides of the seat-portion, neither, however, requiring to be reversible, as the back should be according to my aforesaid patent, but each or either being adapted to be folded flatwise on the seat-portion and being adjustable into position to serve as a seat-back, and both being extensible at the opposite sides of 70 the seat-portion to form the couch for a sleeping-berth. 75

To accomplish my said other objects, (which, however, are in no way dependent on the accomplishment of the first-named, nor of each other) I so form the backs, (for attaining my said second object,) and connect them with the seat at its opposite sides, as to cause them to brace themselves against the seat-portion 80 when lowered to the positions of extending it to form the berth-couch; and (to attain my last-named object) I provide connected links at the ends of the seats, connecting the separable seat-portions with their bases and adapted to be folded transversely across the seat-bases and provided with suitable means for bracing them when extended upward to elevate and support the separable seat-portions in the positions of upper sleeping-berths. 85 90 95

My improvement also involves details of construction and combinations of parts herein-after set forth.

Referring to the accompanying drawings— Figure 1 represents a central longitudinal 100 sectional view in elevation of a broken portion of a car provided with my improvement,

the view being in the nature of a diagram. Fig. 2 represents end-views of two car-seats rendered convertible by my improvements, the one at the left of the figure representing a series, the members of which have their seat-portions adapted to be elevated and supported in position for upper sleeping-berths and the other representing another series, the members of which alternate with the first-named, not being so adapted. Fig. 3 is a view in end elevation of the extensible car-seat, represented in part by dotted lines and showing by full-lines the extensible and folding means for connecting the separable seat-portion with its base and the hinged adjustable backs. Fig. 4 is a broken view in elevation representing the inner side of an end of any one of the car-seats employed in my improvement, showing a guide-slot detail for use in supporting and shifting the adjustable backs. Fig. 5 is a double vertical sectional view taken at the line 5 on Fig. 1 and at the line 5 on Fig. 2, and viewed as indicated by arrows. Fig. 6 is a broken perspective view illustrating the construction of the adjustable seat-back. Fig. 7 is a broken section taken at the line 7 on Fig. 6 and showing locking details with which each seat-back is to be provided. Figs. 8 and 9 are broken views in perspective showing retainer-details for sustaining the distended sectional connections of the separable seat-portions of the seats with their bases.

A denotes my improved vertically extensible car-seat adapted to be converted into an upper sleeping-berth represented in Fig. 1, the seat being shown in Figs. 2 and 3 in its normal, or folded, condition as a car-seat.

A' denotes a car-seat of a series, the members of which alternate with the seats A and are adapted to be converted into lower sleeping-berths, as represented in Fig. 1, from their normal folded condition in which the seat illustrated in Fig. 2 is represented.

Each of the seats A and A' comprises a base *r* of usual or any suitable form and construction, surmounted by a seat-portion *p*, and it has adjustable backs A² and A³, respectively supported, in their positions of backs, at opposite sides of the seat.

The width of the backs of car-seats is ordinarily greater than that of the seat-portions; and inasmuch as I propose to adapt the backs of my improved seats each to be folded flatwise upon a seat-portion *p*, and as they should not, when so folded, project beyond the edges of the seat-portions, I prefer to form each in two sections, the lower one *q* of which corresponds in width, approximately at least, with that of the seat-portion *p*, and the upper one *q'*, which serves to increase the width of the back to any desired extent, being adjustably hinged, (or otherwise connected to fold,) to the upper edge of the section *q* and adapted to be folded under the latter. To adapt the section *q'* of each back to fold flush with the section *q*, I provide in the outer edge-portion

of the latter, in its rear side, an offset in the upholstery to receive the upholstered thickness of the section *q'* when folded. As a suitable means for rendering the head-section *q'* adjustable on its hinge I may employ the mechanism illustrated in detail in the upper portion of Fig. 7 and comprising a spring-plate *t* fastened at one end to the inner side 70 of the end-bar of the frame of the section *q'* and carrying toward its opposite end the thumb-piece *t'*, passing through an opening *x* in the said end-bar, and a locking-lug *t*² passing through an opening *x* in the end-bar, 80 below the opening *x*, into a socket *v*, or opening, in the adjacent portion of the frame of the lower section *q*. As many of the openings *v* as desired may be provided, in an arc 85 concentric with the hinge-center *v'* to adapt the section *q'* to be held in any position, such as represented by dotted lines, to which it may be adjusted to serve as a head-piece, particularly when the back is in its lowered position of forming a portion of a sleeping-berth 90 couch, as hereinafter described. To permit the adjustment, the section *q'* is freed by pressing against the protruding thumb-piece *t'* to withdraw the locking-lug *t*² from an opening *v*.

The backs A² and A³ of each seat are hinged to opposite sides thereof in a manner to adapt either, depending on the direction of motion of the car, to be adjusted into position to serve as a seat-back, and permit the other to be folded flatwise on the seat-portion *p*; and to adapt both to be extended flatwise or horizontally from the seat-portion and form a sleeping-berth couch. Owing to the seam afforded between the adjacent edges of the 100 back-section *q'*, when folded, and back of its receiving offset in the section *q*, the back should not be folded against the seat-portion *p* with the seam-side uppermost, since discomfort might ensue, in consequence, to the 105 occupant. Accordingly I adapt the back to be folded with its seamed side down, as follows: In the inner side of the seat-frame, at each end of the seat, I provide a guide-groove *o* (see Fig. 4), of the general shape of an inverted **U**, the ends of which afford sockets for journals *n* extending outward from the inner lower corners of the frame of the back-section *q*. These journals extend into the adjacent guide-grooves *o* and rest in the corresponding end-sockets thereof when the back is in its normal back-serving position, wherein it is held by a spring fastener, such as is illustrated in detail at the lower part of Fig. 7, but which details, being and operating (except that the locking-lug enters a socket in the seat-arm) like those in the upper portion of the figure for holding the back-section *q'* in any adjusted position, need not be minutely described.

To fold a back down against a seat-portion *p* (which is thereby thickened and supplemented, accordingly), it is released from its locked condition and raised at its journals *n*

in the guides *o*, in which it is moved to the upper ends of the guides at the opposite side of the seat, there attaining a position adapting it to be lowered on the journals *n* upon the seat-portion *p* with its rear or seamed side downward.

To convert the seats *A* and *A'* respectively into upper and lower sleeping-berths, their backs *A²* and *A³* are adjusted into positions 10 of extending flatwise or horizontally from the opposite sides of the seat-portions, in which positions they are braced, without requiring any further support, by the inner flat edges of the backs meeting the adjacent 15 outer, or back and front, sides of the seat-frame. In converting the seats *A'* into lower sleeping-berths, no further manipulation of the backs is required; but for converting the seats *A*, alternating with them, into upper 20 sleeping-berths, the seat-portions *p* must be adapted to be raised (carrying with them the backs) and supported in their elevated position. This may be accomplished by the mechanism for the purpose set forth in my afore- 25 said former patent, though I show herein and desire to claim therefor other means of which the following is a description, with reference, particularly, to Figs. 1, 2 and 5:

Folding connections *B* and *B'*, each formed 30 with pivotal links, *m* and *m'* (two links for each set of the connections being sufficient, though more may be employed) are pivotally connected at their opposite ends respectively near corresponding corners of the seat-frame 35 and the seat-portion, as indicated at *l* and *l'*, and are adapted, in the manner of a toggle-lever, to fold inward across the seat-base. Thus one folding connection, say *B*, connects the seat-portion with the seat-base near their 40 forward corners, and the other, *B'*, connects them near their rear corners, both connections being at the outer end of the seat, and one connection, as *B'*, being fastened to fold in a plane farther in, or toward the car-wall, than that in which the connection *B* folds.

The separable seat-portion *p* of each seat *A* may have the same supporting means at its inner or wall end that is shown and described in my aforesaid former patent, or any 50 other suitable means for the purpose, including the connections *B* and *B'* already described; but the latter do not require to be shown and minutely explained in that position, as the same would be mere duplication 55 of the illustration and description thereof herein contained.

With the connections *B* and *B'* distended in supporting the seat-portions *p* of the seats *A*, in elevated, upper-berth, position, to hold 60 them against tipping toward the car-aisle I provide a suitable retainer *k* (see Fig. 8) on the wall of the car for each connection, in proper location to receive it when unfolded and hold it in the way of reinforcement. In 65 the elevated positions of the said seat-portions, moreover, the distended connections *B* and *B'* require to be braced against collaps-

ing at their joints, for which purpose any of various means may be employed, though I show for the purpose a frame *C* hinged at one 70 end to the outer or aisle-end of the bottom of the frame of the seat-portion and which drops on its hinge, when the seat-portion is raised, into vertical position within the confines of the distended connections *B* and *B'*, and has 75 a cross-piece *i* to render the brace a ladder for use in climbing into the upper berth, and at its sides are spring-catches *h* (see Fig. 9) adapted to engage, automatically, the distended connections and hold the frame in place 80 to brace them against collapsing. When the upper berths are again folded up into seats *A*, the brace-frames *C* are released by disengaging the catches *h* from the sectional connections *B* and *B'*, to permit the latter to collapse 85 and be folded across the seat-base.

As in my said former patent, the arrangement of the seats *A* and *A'* causes the upper and lower berths mutually to overlap one another, since it brings the head of one lower 90 berth and the foot of the adjacent one to meet more or less closely below the center of an upper berth; and the separation of the sleeping-berths may be produced by any suitable adjustable and removable means, such as curtains (not shown) hung between them. 95

From the foregoing it will be seen that my present improvements afford the following advantages over the construction described and shown in my aforesaid former patent: First, 100 the seats have all the parts, required for the conversion, adjustably and permanently connected together by means which may be readily employed with the other features of my former construction, thereby facilitating the 105 conversion and affording a more convenient construction; second, mainly as an incident of the permanent connection of the parts, the backs in their horizontal positions as extensions of the seat-portions to form the couches, 110 are self-supporting, thereby dispensing with separate supporting means for them, such as the pendent straps in my patent; and, third, another form of extensible and folding connection between the separable seat-portions 115 of the seats and their bases is provided, which is adapted for use with the other features in my former patented construction and with those of my present improvement.

What I claim as new, and desire to secure 120 by Letters Patent, is—

1. A convertible car-seat provided with backs, for its opposite sides, folding on the seat-portion and adjustable to form couch-extensions at opposite sides of the seat-portion, 125 substantially as described.

2. A convertible car-seat provided with backs, for its opposite sides, folding on the seat-portion and adjustable to form couch-extensions at opposite sides of the seat-portion 130 and self-supporting in their said adjusted-positions, substantially as described.

3. A convertible car-seat provided with folding backs, for its opposite sides, shiftable

- across the seat to fold on the seat-portion with the rear sides down, and adjustable to form couch-extensions at opposite sides of the seat-portion, substantially as described.
5. A convertible car-seat provided with backs, for its opposite sides, formed with folding sections and folding on the seat-portion and adjustable to form couch-extensions at opposite sides of the seat-portion, the outer 45 sections of the backs being adjustable to a desired angle with relation to the inner sections, substantially as described.
5. In a convertible car-seat, the combination with the base, of a seat-portion separably supported thereon, a connection between the seat-portion and base formed in sections folding across the base and extensible upward to elevate the seat-portion into and support it in position for an upper sleeping-berth, and 50 means for bracing the extended connection, substantially as described.
6. A convertible car-seat comprising, in combination with the base, a seat-portion having a folding connection with the base, upwardly extensible to elevate the seat-portion into and support it in position for an upper sleeping-berth, and backs, for the opposite sides of the seat, folding on the seat-portion and adjustable to form couch-extensions at 55 opposite sides of the seat-portion, substantially as described.
7. A convertible car-seat comprising, in combination with the base, a seat-portion having sectional connections near its corners with the base near its corners, said connections folding in the direction across the base and being upwardly extensible to elevate the seat-portion into and support it in position for an 60 upper sleeping-berth, bracing-means for the extended sectional connections, and backs, 40 for the opposite sides of the seat, folding on the seat-portion and adjustable to form couch-extensions at opposite sides of the seat-portion, substantially as described.
8. In a convertible car-seat the combination with a base *r* supporting a seat-portion *p*, of the end-portions of the seat-frame having guides *o*, backs *A*² and *A*³ formed of adjustable hinged sections *q* and *q'* and journaled in the guides and provided with fastening 45 means for holding them in their positions of backs at opposite sides of the seat-portion, and fastening means for the back-sections *q'* in their adjusted positions, substantially as described.
9. In combination with a car, a series of alternating seats *A* and *A'* convertible, respectively, into upper and lower sleeping-berths, each having a seat-portion *p* provided with folding backs *A*² and *A*³ for its opposite sides, 65 shiftably journaled thereon and adjustable to extend the couch-portions in forming upper and lower sleeping-berths, wherein the said extensions of the two mutually overlap each other, the seat-portions *p* of the seats *A* 60 being separable and connected with their bases by sectional folding connections *B* and *B'* extensible upward to elevate the seat-portions into and support them in position for upper sleeping berths, and means for bracing 70 the extended connections, substantially as described.

JAMES D. MORRISON.
